Edgar V. Atter

UNITED STATES PATENT OFFICE.

PETER J. EISEMANN, OF BROOKLYN, NEW YORK.

DESIGN FOR A LAUNDRY-BAG.

50,469.

Specification for Design.

Patented Mar. 20, 1917.

Application filed January 27, 1917. Serial No. 145,013. Term of patent 7 years.

To all whom it may concern:

Be it known that I, PETER J. EISEMANN, a citizen of the United States, and residing in Brooklyn, in the county of Queens and State of New York, have invented a new, original, and ornamental Design for a Laundry-Bag, of which the following is a specification, reference being had to the accompanying drawing, forming part thereof.

The figure is a perspective view of my newly designed laundry bag.

I claim:

The ornamental design for a laundry bag as shown.

PETER J. EISEMANN.

Witnesses:

C. E. MULREANY,

H. E. THOMPSON.
